UNITED STATES PATENT OFFICE.

AMENZO GRIFFITH, OF SPRINGFIELD, AND HENRY A. BURBANK, OF WESTFIELD, MASSACHUSETTS.

RINGING-OFF DEVICE FOR TELEPHONES.

SPECIFICATION forming part of Letters Patent No. 394,173, dated December 11, 1888.

Application filed August 2, 1888. Serial No. 281,739. (No model.)

To all whom it may concern:

Be it known that we, AMENZO GRIFFITH and HENRY A. BURBANK, citizens of the United States, residing, respectively, at Springfield and Westfield, in the county of Hampden and State of Massachusetts, have invented new and useful Improvements in Ringing-Off Devices for Telephones, of which the following is a specification.

- 10 This invention relates to telephone call-boxes, and pertains to improvements therein, having for their object the provision of devices connected with or attached thereto, whereby the instrument automatically causes 15 an alarm-bell to be rung in the central office when the parts thereof, after a conversation, are returned to their normal positions, said alarm being termed, ordinarily, "ring off," and thereby the office is told that the use of 20 the instrument from which said alarm is given has ceased.

In the drawings forming part of this specification, Figure 1 is a front elevation of an ordinary telephone - box having the cover 25 partly broken away, and having automatic "ringing-off" devices applied thereto embodying our invention, said figure illustrating, also, an electric circuit and an alarm-bell in connection with said telephone-box. Figs. 2, 3, 30 and 4 illustrate detail parts of the improvements, as hereinafter fully described.

In the drawings, A indicates the telephone call-box of the ordinary well-known construction, of which B is the metallic lever, on the 35 outer or free end of which the usual receiver is hung when the instrument is not in use. Said lever is pivoted by one end to the inner side of the box, as shown, and its free end projects through the opposite side of the box, 40 and is bifurcated or otherwise conveniently formed to provide for hanging said receiver thereon, as aforesaid. A spring, 2, is attached to the box and to the said lever B, to swing its free end upward to the position shown in 45 Fig. 1, when the receiver is taken off from the lever by a person wishing to use the instrument. The replacing of the receiver on said lever swings its free end downward, or to its normal position, when the instrument is at rest. 50 Lever B is connected by suitable conductors, $x x$, through the post 3, with any suitable elec-

tric generator, a local battery, 4, being indicated as such in Fig. 1. On lever B is firmly secured, by a suitable metallic connection, a metal hook, 5, which, by the said vibratory motion of said lever, is given a reciprocating vertical motion.

A flexible metallic arm, 6, is attached by one end to the inner side of the box A, and extends therefrom in a line with the lever B, 60 its free end reaching somewhat past the end of the hook 5, as shown. One side of the free end of said lever has its metallic side exposed to contact with the end of said hook when the latter moves downward past it, the 65 arm being so set, as shown in Figs. 2, 3, and 4, that it presents its uncovered side at an incline to the end of said hook, and thereby the latter, in moving downward from the position shown in Figs. 1 and 2 to that shown in Fig. 70 3, will have a sliding contact with said arm, the end of the latter springing back to the position shown in Fig. 3 after the hook 5 leaves it. Figs. 2 and 3 are sectional views of said lever B, hook 5, and flexible arm 6, on the line $x x$, Fig. 1, showing said lever and hook in the two above-referred-to positions. The said arm 6 has applied to one side thereof a non-conducting substance, 7—such as hard rubber or similar material—so that when the 80 lever B swings upward from the position shown in Fig. 3 to that shown in Fig. 2 the hook 5 shall slide on said non-conductor and have no electrical contact with the arm.

Fig. 4 illustrates the arm 6 made a little 85 wider than those shown in Figs. 2 and 3, and having a longitudinal slot or a perforation in it, through which a portion of the non-conducting material 7 protrudes, as shown, leaving metallic surfaces $a a$ each side of the centrally-disposed material 7, with which the end of the hook 5, in its said downward motion, is brought successively into contact. The fixed end of the arm 6 has an electric connection 90 with any convenient part of the line 8, leading to the central office, by a conductor, 9, and any suitable alarm-bell at said office is connected in said line, one end of the latter being grounded, as shown, and one pole of said battery 4 being also grounded, an electric circuit 95 is formed, in which are included the hook 5, the flexible arm 6, and said alarm-bell.

The operation of our improvements is as follows: The positions of the lever B and the hook 5 before said receiver is taken from the protruding end of said lever, as aforesaid, are shown in Fig. 3. Upon removing the receiver spring 2 swings the free end of lever B upward, as described, and in its ascent the end of hook 5 strikes the insulated side 7 of said lever, springing the latter slightly, and passes by it. The said arm then springs back to the position shown in Fig. 2, with its metallic side directly under the end of hook 5. When the person has concluded the telephone conversation and rehangs the receiver on the end of lever B, thereby imparting to it a downwardly-swinging movement, the end of hook 5 is made to move against the metallic side of arm 6, making an electric connection therewith, closing the aforesaid electric circuit and causing the said alarm-bell to be rung, which announces to the central office automatically that the use of the instrument has ceased.

The provision of the above-described improvements, whereby said alarm-bell is rung by hanging on the receiver, obviates the necessity of ringing in a special notice to the office when the person has ceased to use the instrument, and prevents the frequent neglect of persons to give such notice, to the great convenience of the central office.

The construction described of the hook 5 and the arm 6, by the up-and-down movement of the hook, whether as shown in Figs. 2 and 3 or in Fig. 4, provides for a make-and-break connection in the said electrical circuit of which they form a part; but the construction shown in Fig. 4 differs slightly from the others named, in that it provides for two separate contacts of said hook with the metallic face of the arm 6 during its downward movement,

thereby causing the said alarm-bell to ring twice instead of once, as in the arm-construction shown in Figs. 2 and 3.

It is obvious that in lieu of an alarm-bell signal, indicators of other descriptions may be employed, such as the well-known dropping numbered disks, the same, however, being merely equivalents of the bell, but may in some instances be preferably employed.

What we claim as our invention is—

In an automatic ringing-off apparatus for telephone systems, in combination, the call-box, the flexible arm 6, supported therein, having a portion thereof in an inclined plane, one side thereof being formed of material for an electrical conductor, and the other side thereof being formed of material for a non-conductor, the swinging receiver holder-arm provided with the hook 5, so located on said arm that when the latter is in its normal depressed position or in its uppermost position said hook will be out of contact with said arm, but whereby in its passage from its normal to its upper position said hook will pass into and out of contact with the non-conductor side of said flexible arm, and on the return movement of said arm said hook will pass into and out of contact with the conductor side of said arm, the central-office signal-indicator, the line-connection between same and said flexible arm, a local electrical generator and a grounded conductor leading therefrom, and a connection between same and said holder-arm hook, substantially as and for the purpose described.

AMENZO GRIFFITH.
HENRY A. BURBANK.
